UNITED STATES PATENT OFFICE.

DAVID JOHN SCOTT, OF PLAINFIELD, NEW JERSEY, ASSIGNOR TO ISABELLA SCOTT
AND DAVID J. SCOTT, EXECUTORS OF THE ESTATE OF WALTER SCOTT, DECEASED.

PRINTING MACHINE.

Application filed February 2, 1917. Serial No. 146,213.

This invention relates to web printing machines and in particular to printing machines having a plurality of individually operable printing units.

5 Many efforts have been made in the art of printing to design a single, self-contained, printing machine having the capacity and adaptability necessary to meet any requirement likely to be made in producing all of 10 the constantly varying combinations of pages and sections that constitute the different editions of a modern metropolitan newspaper. Such efforts have invariably resulted in the design of machines that have proven 15 slow and cumbersome in operation chiefly by reason of the location of the paper rolls in positions in which they were difficult to manipulate, the threading of the web leads in crowded and inaccessible stretches, and the 20 general failure to so co-ordinate the different printing units as to provide for rapid changes in the co-operative grouping thereof to produce any required edition whether or not other editions were at the moment being 25 printed in the same machine.

The failure of manufacturers to produce a commercially successful machine of this type because of the sacrifice of rapid and easy operation has made it necessary heretofore 30 for newspaper publishers to install a sufficient number of individual presses to print the largest edition produced, and in addition, it was necessary to have each of such presses of sufficient size to print an edition having 35 the largest number of pages that must be produced at one time. The obvious result of this was the necessity for providing a much larger equipment than could be efficiently used since there was occasion to use 40 the whole number of such presses only at comparatively infrequent intervals.

The large machines of this type were not readily operable in small individual units without a considerable adjustment of parts. 45 Also when operating at full capacity as a single printing unit, it was obviously necessary to feed each machine from a great many rolls of paper, and there was no alternative except to stop the operation of the entire 50 press as each roll became exhausted. In a machine feeding from eight rolls, it will be seen that it was practically impossible to avoid stopping the press eight times during the period, approximately twenty minutes, 55 required to use up a roll, since it is compara-

tively unusual for two rolls to become exhausted at the same moment. This resulted, of course, in a great loss of efficiency while the machines were actually operating, and this coupled with the occasion for allowing a 60 number of the presses to be wholly idle for a considerable portion of the time, called for the investment of an unnecessarily large outlay of capital in the printing machinery equipment. 65

One of the objects of the invention is to provide a single, self-contained printing machine with a plurality of printing units having the combined capacity and the adaptability to produce the work of the several 70 separate machines heretofore required in a newspaper printing plant and which will be free from the objections noted.

Another object is to provide a printing machine having a plurality of printing units, 75 or press sections, which can be connected to operate as three octuples, four sextuples, or six quadruples, or in any other combination possible with the given number of printing units. 80

A feature of the invention is the provision of a printing machine having a plurality of printing units operable individually or in groups, and a plurality of driving units any 85 of which can be operatively connected to any printing unit or to any group of printing units.

Still another object is to provide a printing machine having a plurality of individually or collectively operable printing units 90 arranged in horizontal alinement and in such relation to the driving mechanism that no part of the driving mechanism projects into the space beneath the printing units.

With these and other objects in view the 95 invention consists mainly in the provision of a printing machine having twelve printing units which can be operated individually or in any combination to form any product required in the production of a modern 100 metropolitan newspaper. With the twelve printing units are combined a plurality of driving units and a plurality of folders so arranged that any driving unit or folder, or group of driving units and folders, can be 105 driven from any given driving unit. Other features of the invention will be referred to as the specification proceeds.

In the accompanying drawings there are illustrated two embodiments of the inven- 110

tion but it is to be understood that the invention may be carried out by other embodiments different from those selected for illustration.

5 Figures 1 and 2 together comprise a plan view of a machine embodying the invention and showing one form of the driving mechanism used, and with the printing units, and the associating and folding mechanism omitted for the sake of clearness.

10 Figures 3 and 4 together comprise a side elevation of the machine, looking in the direction of the arrow 3 in Figure 7 with parts removed for the sake of clearness, and arranged to operate in quadruple press units.

15 Figures 5 and 6 together form a diagrammatic plan view of the machine showing the relation of the printing units, and the associating and folding mechanism.

20 Figure 7 represents an end elevation of the machine looking in the direction of the arrow 7 in Figure 4.

25 Figures 8, 9 and 10 together show a side elevation of the machine with parts removed for the sake of clearness and showing one method of threading the web for the operation of the machine in octuple press units.

30 Figure 11 is a diagrammatic view of a portion of the machine showing a method for threading the web in the operation of the machine in sextuple press units.

35 Figure 12 is an end view of a set of folders looking in the direction of the arrow 12 in Figure 8.

40 Figures 13, 14 and 15 together show a plan view of a modified form of driving mechanism.

45 Figure 16 is a view of a portion of the machine showing one of the modified forms of driving units in side elevation.

50 Figure 17 is a diagrammatic view of a portion of the machine taken along the arrow 17 in Figure 15 and showing an end view of the modified form of driving mechanism.

55 In the preferred embodiment of the invention shown most comprehensively in Figures 1-2, 3-4, and 5-6 of the drawing, there is disclosed a multi-unit printing machine having twelve individual printing units, or press sections, the general relative location of which is indicated by the reference numerals 1-2, 3-4, 5-6, 7-8, 9-10 and 11-12. It will be seen that the twelve printing units are thus arranged in two parallel rows of six units each. Preferably each printing unit consists of two four-page-wide

60 printing couples, capitated to print papers having varying numbers of pages up to sixteen, and two such units can be operatively connected together to form a quadruple press specially useful in printing papers of ten, twelve, fourteen or sixteen pages in one

65 section, and twenty-eight and thirty-two

page combinations in a plurality of sections. In order to facilitate the operation of the printing units as quadruple presses, the twelve printing units are preferably arranged in six groups of two closely associated printing units each, and each such group is provided with a single folder and a single driving mechanism. That is, the printing machine shown and described, comprises twelve printing units with which are associated six folders, and six driving units.

70 In the grouping of the printing units into the six quadruple press units referred to, the printing units 1 and 3 are operatively associated with the folder 13 and the driving unit 19 to form a quadruple press; the printing units 2 and 4 with the folder 14 and the driving unit 20; the printing units 5 and 7 with the folder 15 and the driving unit 21; the printing units 6 and 8 with the folder 16 and the driving unit 22; the printing units 9 and 11 with the folder 17 and the driving unit 23; and the printing units 10 and 12 with the folder 18 and the driving unit 24. With an arrangement such as this, as shown in part in Figures 3 and 4, it will be clear that, in effect, the machine has been converted into six independent, individually operable, quadruple presses, any one of which can be operated singly or any number of which can be operated simultaneously on the same or on different work. It will be equally clear that the stopping of any one of the six quadruple press units for repairs or for the supply of paper interferes in no way with the operation of the remaining units.

75 With an arrangement of printing units and folders such as the one just described, it will be apparent that the quadruple presses at the left-hand end of the machine which feed to the folders 13 and 14, together with the quadruple presses at the right-hand end which feed to the folders 17 and 18 constitute what may be termed end folder machines, while the central printing units forming the quadruple presses which feed to the interposed folders 15 and 16 are central folder machines.

80 Not only can the twelve printing units going to make up the machine be conveniently grouped together to form six quadruple presses, but by means of suitable coupling connections any other desired arrangement and grouping of the printing units and driving mechanisms may be made to comply with the requirements of present-day newspaper work.

85 The twelve printing units can also be readily arranged in groups of three to form four sextuple presses, especially useful in producing eighteen, twenty, twenty-two, or twenty-four page papers in one section, and also thirty-six, forty, forty-four, or forty-eight page combinations in two or more sec-

120

125

130

tions. In such an arrangement as indicated in part in Figure 11 the printing units 1, 3 and 5 are operatively associated with the folder 13 and the driving unit 19 to form one sextuple press; the printing units 2, 4 and 6 with the folder 14 and the driving unit 20; the printing units 7, 9 and 11 with the folder 17 and the driving unit 23; and the printing units 8, 10 and 12 with the folder 18 and the driving unit 24. With this arrangement the machine has been divided into four independent, individually operable sextuple presses, any one of which can be operated singly, or any number of which can be operated simultaneously.

It will be seen that when the printing units are grouped in this manner to operate as sextuple presses that each sextuple unit operates as a central folder machine, and that the centrally located driving units 21 and 22, together with the corresponding folders 15 and 16, are not used but are held in reserve.

As is well known in the art a third frequently used printing unit is the octuple press and the coupling connections employed in the printing machine disclosed permit of the division of the twelve printing units into groups of four to form three octuple presses especially adapted to produce twenty-six, twenty-eight, thirty, or thirty-two page combinations in either one or more sections, or fifty-two, fifty-six, sixty, and sixty-four page combinations in a plurality of sections.

To obtain such an arrangement, as shown in Figures 8, 9 and 10, the printing units 1, 2, 3 and 4 are operatively associated with either one or both of the driving units 19 and 20 and with either one or both of the folders 13 and 14 to form an octuple press. There is a like association of the printing units 5, 6, 7 and 8 with the driving units 21 and 22 and the folders 15 and 16 to form a second octuple press, and of the printing units 9, 10, 11 and 12 with the driving units 23 and 24 and the folders 17 and 18 to form a third octuple. The three octuple presses thus provided are capable of individual or combined operation as may be found desirable.

While specific arrangements of the printing units of the machine into groups to produce the three most generally used machines, that is, the quadruple, the sextuple, and the octuple press, have been described, it is possible with the apparatus shown to arrange an almost unlimited number of other combinations so that press groupings or arrangements of any desired capacity can be readily secured. For example, the printing units may be coupled up to simultaneously produce an octuple, a sextuple, and a quadruple press product, or any combination of such products, within the capacity of the number of printing units in the machine.

Another example is the so-called decouple combination by means of which products up to eighty pages may be obtained. This is accomplished by combining units 1, 2, 3, 4 and 5 with one or more of driving units 19, 20 and 21 and with either folders 13, 14 and 15 as one decouple machine and combining units 7, 9, 10, 11 and 12 with one or more of driving units 23 and 24 and with either folders 15, 17 or 18 as another decouple machine. In these circumstances the remaining units 6 and 8 can be coupled up with driving unit 22 and folder 16 to run as an independent quadruple; or, instead of having two decuples and a quadruple, the machine may be arranged as one decouple comprising units 7, 9, 10, 11 and 12 as previously described and the remaining units may be arranged as one octuple comprising units 1, 2, 3 and 4 and one sextuple comprising units 5, 6 and 8, such sextuple using one or both of motor units 21 and 22 and using folder 16 or 18; or, the machine may be run as two double sextuples by combining units 1, 2, 3, 4, 5 and 6 with one or more driving units 19, 20, 21 and 22 with folders 13, 14, 15 or 16 as one double sextuple and combining units 7, 8, 9, 10, 11 and 12 with one or more driving units 23 and 24 with folders 15, 16, 17 or 18 as another double sextuple.

In order to operate any desired combination of printing units it is desirable to provide driving connections between the printing units and the driving units which will make it possible to drive any printing unit or group of printing units from preferably any given driving unit wherever located. These driving connections include as the main driving members the two lines of sectional shafting 80 which extend substantially from end to end of the machine as shown in Figures 1, 2 of the drawing. By means of suitable coupling members, which will be hereafter more specifically referred to, the various shaft sections may be interconnected to form any desired driving connection preferably between any driving unit and any printing unit or group of printing units.

It will be seen, by referring to Figures 1-2 and Figure 7 of the drawing, that the entire driving equipment, including the driving units and the shafting 80, is mounted in a pit beneath the framework of the machine, and that the two lines of shafting 80 are placed between the two parallel rows of printing units and underneath the removable floor, or grating 81, of the central passageway that extends the length of the machine. By this arrangement, not only are the main driving shafts placed outside the lateral boundary lines of the press units where they will offer no obstruction to the passage of a web to a printing unit from a roll supported at a lower point, but they are

rendered easily accessible from the central passageways so that it is a simple matter to quickly manipulate the coupling members in forming the various driving connections. In the second modification of the invention shown in Figures 13 to 16 of the drawing, the motor equipment, as well as the driving shafts, is so mounted that no part of it extends into the space beneath the printing units. To provide for this the six driving units, instead of being mounted beneath printing units as in the modification shown in Figures 1 to 4 and 8 to 10, are mounted beneath the six folding devices. This construction meets the demands of newspaper plants in which the paper rolls are mounted in a basement or other room beneath the press room, so that the space beneath the printing units must be kept clear for the passage of the webs.

By reference to Figure 7 of the drawing the arrangement of the printing couples in each printing unit can be seen. The primary printing couple includes a plate cylinder 62, supplied with ink from an ordinary form of inking mechanism 63, and printing one side of the web 64 as it passes over the impression cylinder 65. There is also a secondary printing couple comprising plate cylinder 66, supplied with ink by the inking mechanism 67, and printing the other side of the web 64 as it passes over the impression cylinder 68.

In the arrangement of the printing couples in each printing unit as shown in Figure 7, it will be seen that each primary plate cylinder 62 is located at a convenient height adjacent the central passage between the two parallel lines of printing units, and from which they can be easily reached. Each secondary plate cylinder 66 is located at a somewhat higher elevation at the outer side of the machine where it is accessible from the adjacent platform 70. The secondary plate cylinders, together with their inking mechanisms 67 are mounted in the elevated position shown in order to make room underneath for the web rolls 71 which, therefore, do not require any floor space outside the confines of the machine framework and, in addition, are easily accessible at all times.

The four-page-wide web, printed on both sides, is led upwardly from the corresponding printing unit, such as 1 in Figure 3, over the guide roller 95 and thence around the lower roller 73 where the web is centrally divided by any suitable means at the point 96. In all three press arrangements shown the two two-page-wide web sections from the printing unit 1 are led from the lower rollers 73 to the corresponding lower angle bars 69, shown in dotted lines in Figure 5, by which they are given a quarter turn and diverted rearwardly, one section passing about the lower centrally placed web

roller 72 and the other about the lower rearwardly placed roller 72. It will be seen that the rollers 72 are placed at right angles to the roller 73 and that the two web sections 64, when diverted about the rollers 72, travel 70 in superposed relation forwardly between the upper and the lower sets of angle bars associated with the printing couple 3 and thence to the folder 13. The web from the printing couple 3 takes a similar course and is led 75 from this couple beneath the web sections from the printing couple 1 to the folder 13.

In Figure 11 is shown a method of threading the web when the three printing units 1, 3 and 5 are associated to form a sextuple 80 press combination. The web sections in this arrangement are led from the printing units 1 and 3 to the folder 13 in the manner already described, where they are joined by web sections from the printing unit 5 to form a sextuple press product. It will be seen that the web sections have their direction of travel twice reversed in passing from the printing unit 5 in order to thereby loop the web sections and provide 90 for their regulation in a manner well-known in the art.

In the octuple press arrangement the web sections from the printing units 1 and 3 are also conducted to the folder 13 as indicated in Figure 8, but, in addition, the web sections from the printing units 2 and 4 at the opposite side of the machine are led through this folder. In order to effect this, the web sections from the printing units 2 and 4 are carried about the upper guide rollers 73' instead of the lower ones, as is the case with the units 1 and 3, and from the rollers 73' the web sections are led to the other side of the machine and diverted about the upper set of angle bars 69 of the printing units on that side of the machine. This arrangement is indicated generally in the end view of the machine shown in Figure 7. As shown in Figure 8 the further course of the web sections from the upper set of angle bars and around the upper guide rollers 72 and thence to the folder 13 is similar to that of the web sections from the printing units 1 and 3 so that the eight sections enter the folder 13 in a superposed relation as is indicated in Figure 8.

The web threading arrangement described for the printing couples at the left-hand end of the machine can, of course, be utilized for the remaining units. The threading, however, for the central group of printing units 5, 6, 7 and 8 is completely reversed for the sextuple arrangement in order to bring the web sections out to the folders 13 and 17 instead of directing the web to the centrally placed folder 15 in the other two normal press combinations.

The three methods shown for directing the web from the printing units to the fold-

ers are intended only for examples, and out of the almost endless number of possible paths through which the web sections may be directed, it is a simple matter to choose 5 any desired combination.

By referring to Figures 5 and 6 of the drawing the general arrangement of the angle bars 69 and the web rollers 72 comprising the associating mechanism located over 10 the central passage between the parallel lines of printing units and accessible from the platforms 85 of Figure 7 as well as the passageway, can be seen. The arrangement and construction of the associating mechanism is such that the web from any printing 15 unit may readily be directed to any of the folding devices by a single quarter turn, as will be obvious.

As will be seen the quadruple press units 20 at the left-hand end of the machines form an end folder machine and the quadruple press units at the opposite end of the machine are of the same type. However, the two printing units 5 and 7 at the central 25 part of the machine have the corresponding folder 15 interposed between them so that the webs from these two units do not travel together until they arrive at the folder. These units form, therefore, a central 30 folder machine.

It will be noted that there are auxiliary 35 folders 75 mounted over the main folders 13, 14, 17 and 18 in Figures 3 and 4 and over all the main folders in Figures 8, 9 and 10. These auxiliary folders are shown for the 40 reason that they provide means for producing certain desirable combinations that have been found useful in meeting the requirements of a number of the more important newspapers. It is obvious that these auxiliary folders may be omitted altogether or 45 that they may be placed over different main folders, or that all the main folders may have auxiliary folders mounted over them as may be found most useful.

In Figure 12 of the drawing is shown a face view of the group of folders shown in side elevation in Figure 8 of the drawing. Each folder comprises the usual former 86 50 which makes the primary longitudinal fold in the web. The paper passes down over the formers between the rollers 87 from which it passes between cutting cylinder 88 and the transverse folding cylinder 89 to 55 any suitable delivery mechanism. It will be clear that the four folders shown in this figure can be arranged to produce different products, and, if desired, three of them can be used merely to longitudinally fold corresponding webs all of which can be transversely folded and cut by the devices associated with either of the folders 13 or 14. An arrangement such as this is illustrated and 60 it will be seen that the longitudinally folded web sections 64 pass from the former 86 of

folder 75 through the rollers 87 and thence about the tension roller 96, thence to the upper guide roller 97, the lower guide roller 98 and over one of the rollers 87 of the folder 13. Likewise the web sections 64 from the folder 75' pass over the guide roller 99, the tension roller 100, the guide roller 101, and thence about one of the guide rollers 87 of the folder 14. From this point the web sections from the folders 75' and 14 travel 70 about the tension rollers 102 and guide roller 103 to the rollers 87 of the former 13 where the webs from all four folders are associated to be transversely cut and folded by the cutting cylinder 88 and folding cylinder 89 of that folder. The folders shown are of well-known construction and different types of folding devices can be used without departing from the invention shown and described. Any suitable mechanism, not 85 shown, may be used for driving the folders from the drive shafts 80 and preferably the gears 90 and 91 on the drive shafts form a part of such driving mechanism.

In the modification of the invention shown in Figures 1 to 4 and 8 to 10 of the drawing each of the driving units is located directly underneath a printing unit, the six driving units 19, 20, 21, 22, 23 and 24 being mounted beneath the printing units 3, 4, 5, 6, 9 and 10 respectively while, as has already been pointed out, in the modification shown in Figures 13 to 16, the driving units are mounted beneath the folders 13, 14, 15, 16, 17, and 18. Each driving unit preferably 90 includes variable speed mechanism whereby a gear ratio that will provide for driving the corresponding printing unit at a slow speed in starting, can be utilized, and which can be eliminated when the inertia opposed to starting has been overcome. This general type of driving mechanism is the well-known Kohler system as installed by the Cutler-Hammer Mfg. Co., an embodiment of which is shown in the patent to Stone 628,190, July 105 4, 1899. Each driving unit preferably consists of a main motor 55 adapted to directly drive the motor shaft 36, and a smaller starting motor 56 connected to the motor shaft 36 through a gear train including the 110 pinion 57, gear 58, pinion 59 and gear 60 mounted to rotate on the motor shaft 36. The gear 60 is adapted to be coupled to the motor shaft 36 through a ratchet drive indicated generally at 61. Controlling means, 115 not shown, are provided for first starting the small motor 56 to turn the main motor shaft 36 at a relatively slow speed, and then starting the main motor which directly drives the shaft 36 at a higher speed which does not affect the starting motor mechanism by reason of the ratchet mechanism at 61. Preferably, also, current is automatically cut off from the starting motor when 120 it is turned on through the main motor 55. 125

The construction by means of which the various driving units can be coupled to different printing units, or groups of units, will now be described. Preferably each printing couple is directly driven from a vertical shaft 36 carrying at its lower end a bevel gear 36 which meshes with a bevel gear 27 mounted on one of the transverse shafts 28 or 28', 29 or 29', 30 or 30'. It will be seen upon an inspection of Figures 1 and 2 that the transverse shafts 28 are utilized to drive the printing units 1 and 2, and are provided with gears 31 at one end which mesh with gears 32 on the end of the short transverse drive shafts 33. The transverse shafts 33 carry bevel pinions 34 meshing with the bevel pinions 35 on the motor shafts 36. The bevel pinions 35 can preferably be moved along this supporting shaft 36 out of engagement with the bevel pinions 34 to throw the corresponding driving units out of gear. By this construction it will be seen that the driving units 19 and 20 are normally associated with the printing units 1 and 2 respectively and that the corresponding driving units 23 and 24 are similarly associated with the printing units 11 and 12 and this comprises a quadruple press driving connection.

The transverse shafts 29 and 29' from which the printing units 3, 4, 9 and 10 are driven are provided at one end with gears 92 and 92' which also mesh with the gears 32 and 32' carried by the drive shafts 33 and 33', so that the driving units 19, 20, 21 and 22 are also normally associated with the printing units 3, 4, 9 and 10, respectively.

The transverse shafts 29 and 29' are adapted to be coupled together by means of the coupling members 37 and 37' so that, if desired, either of the driving units 19 or 20, or 23 or 24 can be utilized to drive not only the two printing units normally associated therewith, but also the two printing units at the same end and opposite side of the machine. Moreover, the coupling members 37 and 37' provide means for connecting both motor units 19-20, or 23-24 simultaneously to drive the corresponding four printing units in absolute synchronism as an octuple machine.

As has already been stated, in the arrangement of the printing units into groups to form sextuple presses, it is preferred to drive three aligned printing units from a single driving unit, as for instance printing units 1, 3 and 5 from the motor unit 19. In order to convey motion to the printing unit 5 from the driving unit 19, and correspondingly to the printing units 6, 7 and 8 from the driving units 20, 23 and 24 respectively, use is made of the shaft sections 38 and 38' of the shafts 80 which carry bevel gears 39 and 39' meshing with bevel gears 40 and 40' on the transverse shafts 29 and 29'. Through coupling members 41 and 41' the shafts 38 and 38' can be coupled to the shaft sections 42 and 42' which carry bevel gears 43 and 43' meshing with bevel gears 44 and 44' on the transverse drive shafts 70 30 and 30' from which the printing units 5, 6, 7 and 8 are driven. It will be seen that the short shaft sections 42 and 42' can also be coupled by means of the coupling members 45 and 45' to the central shaft sections 75 46. It will be obvious that, when it is desired to drive the printing unit 5, for instance, from the motor unit 19, the corresponding coupling member 41 is placed in shaft coupling position while the coupling 80 members 37 and 45 are disconnected.

In order to drive the central printing units 5-7 and 6-8 from the respective driving units 21 and 22 to form two quadruple press units, the central shaft sections 46 and the coupling members 45 and 45', already referred to, are utilized. In this instance the motor shafts 36 of the motor units 21 and 22 are provided with gears 47 which, through a train of gears 48 and 49 drive the gears 50 on the central shaft sections 46. It will be clear that, by disconnecting the coupling members 41 and 41' and connecting the coupling members 45 and 45', the shaft sections 42 and hence the transverse drive shafts 30 and 30' can be driven to convey motion to the printing units 5, 6, 7 and 8.

The slip gears 51 on the shafts 46 provide for the connection of either motor unit 21 or 22 to the printing units on the opposite sides of the machine, and also serve to assist the operation of the four centrally located printing units in unison when they are being operated as an octuple press. The gears 50 are also slip gears, that is, they can be moved out of mesh with their driving gears 49 to thereby disconnect the corresponding motor from a shaft section 46.

In order to operate the machine in six quadruple press groups from the six individual driving units the coupling members 45 and 45' shown in Figures 1 and 2 are operatively connected and all the remaining clutches, including the gears 51 are disconnected. In connecting up the machine to operate as four sextuple presses the coupling members 37-37', and 45-45' are disconnected while the coupling members 41 and 41' and the gears 51 are connected. This will drive three aligned press units from either motor at the ends of the machine leaving the central motors idle, as will be seen. When operating as three octuple presses the coupling members 41 and 41' are disconnected, all the remaining coupling members and the gears 51 being connected. As will be seen this divides the machine into three units each of which is in effect an octuple press.

In order to disconnect any individual 130

printing couple from the driving mechanism the bevel gear 52 carried by the impression cylinder shaft 53 can be moved out of mesh with the bevel gear 54 on the vertical drive shaft 25. It will be seen that the mere connecting or disconnecting of the bevel gears 52 and 54 may put the corresponding printing unit into or out of operation.

In the modification in which the motor units are shown as mounted underneath the folders instead of underneath the printing units, the method of connecting the driving units to the various printing units differs from that shown in the first modification in that in no instance is a motor connected to one of the main shafts through one of the transverse shafts 29 or 29', but each one of the six driving units is connected directly to an adjacent section of one of the main lines of shafting through the pinion 76 on the motor shaft 36, the intermediate gear 77, and the slip gear 78 on the adjacent section of shafting. By means of this gear the corresponding motor may be thrown into or out of operative connection with the shafting by slipping the gear into or out of mesh with the gear 77, as will be readily understood. In this modification the end shafts 28 and 28' instead of the shafts 29 and 29' are supplied with coupling members 37 and 37', and the shaft sections 38 and 38' are extended and provided with bevel gears 95 and 95' meshing with bevel gears 79 and 79' on the shafts 28 and 28'.

It will be seen that in the invention disclosed a printing machine has been provided which in a simple form and a greatly reduced cost embodies all the advantages possessed by a number of smaller machines. The mounting of all the units at substantially the floor level makes them quickly accessible and enables the user to readily produce the maximum output, regardless of the varying character of the product and of whether it is necessary to operate the machine as octuple, sextuple, or quadruple presses, or as different combinations of these units.

What is claimed, is:

1. In a printing press, the combination of twelve press sections, driving means for said press sections, and means for connecting said driving means with said press sections for driving the press as six quadruples, as four sextuples, or as three octuples.

2. In a printing press, the combination of two press sections arranged in longitudinal alinement with each other, a third press section arranged in alinement therewith, a line of shafting extending longitudinally of said press sections, connections between said shafting and said press sections, means located between said first-named two sections and said third section for driving said shafting for operating said press sections, angle-

bars over which the webs printed by said sections may be turned and associated to run longitudinally of said sections, and means located between said first-named two sections and said third section for giving the associated webs from said sections a longitudinal central fold.

3. In a printing press, the combination of two press sections arranged in longitudinal alinement with each other, a third press section arranged in alinement therewith, a line of shafting extending longitudinally of said press sections, connections between said shafting and said press sections, means located between said first-named two sections and said third section for driving said shafting for operating said press sections, angle-bars over which the webs printed by said sections may be turned and associated to run longitudinally of said sections, means located between said first-named two sections and said third section for giving a central longitudinal fold to the webs, and other alternative means located at the end of said third section for giving a central longitudinal fold to said webs.

4. In a printing press, the combination of two press sections arranged in longitudinal alinement with each other, a third press section arranged in alinement therewith, two other press sections arranged in longitudinal alinement with each other alongside of said first-named two sections, a sixth press section arranged in longitudinal alinement with said second-named two alined sections alongside of said third section, angle-bars over which the webs printed by said sections may be turned and associated as desired to run together longitudinally of said sections at either side of the press, a line of shafting extending longitudinally of the said press sections at each side of the press, connections between said lines of shafting and said sections respectively, means for driving said shafting for operating said press sections, and means located between said third and sixth press sections and the remaining press sections for giving the associated webs from said press sections a longitudinal central fold.

5. In a printing press, the combination of two press sections arranged in longitudinal alinement with each other, a third press section arranged in alinement therewith, two other press sections arranged in longitudinal alinement with each other alongside of said first-named two sections, a sixth press section arranged in longitudinal alinement with said second-named two alined sections alongside of said third section, angle-bars over which the webs printed by said sections may be turned and associated as desired to run together longitudinally of said sections at either side of the press, a line of shafting extending longitudinally of the said press

- sections at each side of the press, connections between said lines of shafting and said sections respectively, means for driving said shafting for operating said press sections, 5 means located at the ends of said third and sixth press sections respectively for giving the associated webs from said press sections a longitudinal central fold, and other means located between said third and sixth press 10 sections and the remaining press sections adapted alternately for giving the associated webs from said press sections a longitudinal central fold.
6. In a printing press, the combination of 15 two aligned press sections, angle-bars over which the webs printed by said sections may be turned and associated to run longitudinally of said sections, means located between said press sections for giving the associated 20 webs a central longitudinal fold, two variable-speed mechanisms, and means for driving said press sections either separately through said two variable-speed mechanisms or in unison through one of said variable- 25 speed mechanisms.
7. In a printing press, the combination of 30 two aligned press sections, angle-bars over which the webs printed by said sections may be turned and associated to run longitudinally of said sections, means located between said press sections for giving the associated webs a central longitudinal fold, and means located between said two press sections for driving said press sections in unison.
- 35 8. In a printing press, the combination of two aligned press sections, two other aligned press sections located alongside of said first-named two sections, angle-bars over which the webs printed by said sections may be 40 turned and associated to run longitudinally of said sections, means located between the aligned press sections at each side of the press for giving the associated webs a central longitudinal fold, four variable-speed mechanisms, and means for driving said press sections either separately through said four variable-speed mechanisms or in unison through one of said variable-speed mechanisms.
- 45 50 9. In a printing press, the combination of two aligned press sections, two other aligned press sections located alongside of said first-named two sections, angle-bars over which the webs printed by said sections may be 55 turned and associated to run longitudinally of said sections, means located between the aligned press sections at each side of the press for giving the associated webs a central longitudinal fold, aligned driving shafts extending longitudinally of the press sections at 60 each side of the press, an intermediate driving shaft between the said aligned shafts at each side of the press, means for connecting each of said intermediate shafts with either 65 or both of the aligned shafts at that side of the press, and means for driving said intermediate shafts.
10. In a printing press, the combination of twelve press sections, driving means for said press sections, and means for connecting said driving means with said press sections for driving the press as four sextuples or as three octuples. 70
11. In a printing press, the combination of two aligned press sections, angle-bars over 75 which the webs printed by said sections may be turned and associated, means located at one end of said aligned press sections for driving either or both of said sections, and other means located at the opposite end of 80 said aligned press sections for alternatively driving either or both of said sections.
12. The combination of twelve press sections, a plurality of motors for driving said press sections, and connecting means between 85 the motors and sections to drive the sections as a plurality of alternative double sextuple groups greater than two, the same section being capable of being optionally included in more than one double sextuple 90 group.
13. The combination of twelve press sections, a plurality of motors for driving said press sections, and connecting means between 95 the motors and sections to drive the sections as a plurality of alternative double sextuple groups greater than two, the same section being capable of being optionally included in more than one double sextuple group or for driving said section optionally 100 in various lesser groupings than double sextuples.
14. The combination of twelve press sections, a plurality of motors for driving said press sections, and connecting means between 105 the motors and sections to drive the sections as two independent decuples and an independent quadruple.
15. The combination of twelve press sections, a plurality of motors for driving said 110 press sections, and connecting means between the motors and sections to drive the sections as two independent decuples and an independent quadruple or for driving said sections optionally in various lesser groupings than decuples. 115
16. In a printing press, the combination of twelve press sections, three motors for driving said press sections, and means for connecting each of said motors with four of 120 said sections to drive the twelve press sections as three octuples.
17. In a printing press, the combination of twelve press sections, a plurality of motors, and connecting means between the motors and sections to operate the sections as six quadruples, as four sextuples, as three octuples or as two decuples and an independent quadruple. 125
18. In a printing press, the combination 130

- of twelve press sections, a plurality of motors, and connecting means between the motors and sections to operate the sections as six quadruples, as four sextuples, as three octuples or as two double sextuples.
19. In a printing press, the combination of twelve press sections, a plurality of motors and connecting means between the motors and sections to operate the sections as six quadruples, as four sextuples, as three octuples, as two decuples and an independent quadruple or as two double sextuples.
20. In a printing machine, the combination of twelve press sections, a plurality of motors, and connecting means between the motors and sections to drive the sections as three octuples or as two decuples and an independent quadruple.
21. In a printing machine, the combination of twelve press sections, a plurality of motors, and connecting means between the motors and sections to drive the sections as three octuples or as two double sextuples.
22. In a printing machine, the combination of twelve press sections, a plurality of motors, and connecting means between the motors and sections to drive the sections as three octuples, as two decuples, and an independent quadruple or as two double sextuples.
23. In a printing machine, the combination of twelve press sections, a plurality of motors, and connecting means between the motors and sections to drive the sections as two sextuples, one octuple and one quadruple, or as three octuples.
24. In a printing machine, the combination of twelve press sections, a plurality of motors, and connecting means between the motors and sections to operate the sections as one decuple, one octuple and one sextuple.
25. In a printing machine, the combination of twelve press sections, a plurality of motors, and connecting means between the motors and sections to drive the sections as a double sextuple, one octuple and one quadruple or as three octuples.
26. The combination of twelve press sections, a plurality of motors for driving said press sections, and connecting means between the motors and sections to drive the sections as a plurality of alternative decuples greater than two, the same section being capable of being optionally included in more than one decuple group.
27. The combination of twelve press sections, a plurality of motors for driving said press sections, and connecting means between the motors and sections to drive the sections as a plurality of alternative decuples greater than two, the same section being capable of being optionally included in more than one decuple group or for driving said sections optionally in various lesser groupings than decuples.
28. In a printing machine, the combination of twelve press sections, a plurality of motors, and connecting means between the motors and sections to drive the sections as one octuple and four quadruples or as three octuples.
29. In a printing machine, the combination of twelve press sections, a plurality of motors, and connecting means between the motors and sections to drive the sections as two octuples and two quadruples or as three octuples.
30. A printing machine comprising: a plurality of printing units, driving means therefor, and means for connecting said driving means to said printing units to operate said printing units in groups consisting of a plurality of octuples, and one sextuple press combination.
31. A printing machine comprising: a plurality of horizontally aligned printing units and folders, and driving mechanism for said printing units and folders including a plurality of driving units and a line of sectional shafting, said driving units being mounted beneath said folders, and said line of sectional shafting extending parallel to the aligned printing units and outside the vertical planes marking the lateral boundaries of said printing units.
32. A printing machine comprising: a plurality of printing units arranged in two parallel rows, driving mechanism for said printing units including a plurality of driving units and two lines of sectional shafting extending parallel to said rows and between the vertical planes marking the adjacent lateral boundaries of the two parallel rows of printing units, and coupling members for forming various driving connections between the driving units and the printing units.
33. A printing machine comprising: a plurality of printing units and folders arranged in two parallel rows, and driving mechanism for said printing units and folders including a plurality of driving units and two lines of sectional shafting extending parallel to the aligned printing units, said driving units being mounted beneath said folders, and said two lines of shafting being located between the vertical planes marking the adjacent lateral boundaries of the two parallel rows of printing units.
34. A printing machine comprising: six printing units arranged in longitudinal alinement, and folders for said printing units so arranged that the two printing units at each end of the aligned units can be operated as an end folder machine and the two centrally located units can be operated as a central folder machine.
35. A printing machine comprising: twelve printing units arranged in two parallel rows, and folders for said printing

- units so arranged that the four printing units at the ends of the rows can be operated as one or two end folder machines and the four centrally located units can be operated as one or two central folder machines. 36. A printing machine comprising: a plurality of printing units arranged in a line, a plurality of folders interspersed between the printing units in said line, and 10 means for so threading the web that any given folder can be associated with adjacent printing units to form either a central folder or an end folder printing press as desired. 37. A printing machine comprising: six printing units arranged in longitudinal alignment, and three folders for said printing units one of which is located between the second and third printing units, another between the third and fourth units, and another between the fourth and fifth units. 38. A printing machine comprising: twelve printing units arranged in two parallel rows, and six folders for said printing units arranged in groups of two, one folder of each group being located between the second and third printing units of each row, another between the third and fourth units, and another between the fourth and fifth units. 39. A printing machine comprising: six printing units arranged in longitudinal alignment, and five folders for said printing units two of said folders being arranged in superposed relation between the second and third printing units, another folder being located between the third and fourth units, and the two remaining folders being arranged in superposed relation between the fourth and fifth units. 40. A printing machine including: a plurality of press sections, a plurality of folders, driving means, and means for connecting said press sections and said folders with said driving means to operate the machine as four sextuples or as three octuples. 41. A printing machine including: a plurality of press sections, a plurality of folders, a plurality of motors for driving said press sections, and means for connecting said press sections and folders with said motors to operate the machine as a plurality of alternative double sextuples greater than two, the same sections being capable of being optionally included in more than one sextuple. 42. A printing machine including: a plurality of press sections, a plurality of folders, a plurality of motors, and means for connecting the sections and folders with the motors to operate the machine as a plurality of alternative double sextuples greater than two, the same section being capable of being optionally included in more than one double sextuple or for driving said sections and folders optionally in various lesser groupings than double sextuples. 43. A printing machine including: a plurality of press sections, a plurality of folders, a plurality of motors, and means for connecting the sections and folders with the motors to operate the machine as two independent decuples and an independent quadruple. 44. A printing machine including: a plurality of press sections, a plurality of folders, a plurality of motors, and means for connecting the sections and folders with the motors to operate the machine as two independent decuples and an independent quadruple or for driving said sections optionally in various lesser groupings than decuples. 45. A printing machine including: a plurality of press sections, a plurality of folders, a plurality of motors, and means for connecting said motors with said press sections and folders to operate the machine as three octuples. 46. A printing machine including: a plurality of press sections, a plurality of folders, a plurality of motors, and means for connecting the sections and folders with the motors to operate the machine as a plurality of quadruples, as a plurality of sextuples, as a plurality of octuples or as a plurality of decuples and an independent quadruple. 47. A printing machine including: a plurality of press sections, a plurality of folders, a plurality of motors, and means for connecting the sections and folders with the motors to operate the machine as a plurality of quadruples, as a plurality of sextuples, as a plurality of octuples or as a plurality of double sextuples. 48. A printing machine including: a plurality of press sections, a plurality of folders, a plurality of motors, and means for connecting the sections and folders with the motors to operate the machine as a plurality of quadruples, as a plurality of sextuples, as a plurality of octuples, as a plurality of decuples and an independent quadruple or as a plurality of double sextuples. 49. A printing machine including: a plurality of press sections, a plurality of folders, a plurality of motors, and means for connecting the sections and folders with the motors to operate the machine as a plurality of octuples or as a plurality of decuples and an independent quadruple. 50. A printing machine including: a plurality of press sections, a plurality of folders, a plurality of motors, and means for connecting the sections and folders with the motors to operate the machine as a plurality of octuples or as a plurality of double sextuples. 51. A printing machine including: a plu-

- rality of press sections, a plurality of folders, a plurality of motors, and means for connecting the sections and folders with the motors to operate the machine as a plurality 5 of octuples, as a plurality of decuples and an independent quadruple or as a plurality of double sextuples.
52. A printing machine including: a plurality of press sections, a plurality of folders, a plurality of motors, and means for connecting the sections and folders with the motors to operate the machine as a plurality of sextuples, one octuple and one quadruple or as a plurality of octuples.
53. A printing machine including: a plurality of press sections, a plurality of folders, a plurality of motors, and means for connecting the sections and folders with the motors to operate the machine in groupings including a decuple, an octuple and a sextuple.
54. A printing machine including: a plurality of press sections, a plurality of folders, a plurality of motors, and means for connecting the sections and folders with the motors to operate the machine in groupings including a double sextuple, an octuple and a quadruple or as a plurality of three octuples.
55. A printing machine including: a plurality of press sections, a plurality of folders, a plurality of motors, and means for connecting the sections and folders with the motors to operate the machine in groupings including a plurality of alternative decuples greater than two, the same section being capable of being optionally included in more than one decuple group.
56. A printing machine including: a plurality of press sections, a plurality of folders, a plurality of motors, and means for connecting the sections and folders with the motors to operate the machine in groupings including a plurality of alternative decuples greater than two, the same section being capable of being optionally included in more than one decuple group or for driving said sections optionally in various lesser groupings than decuples.
57. In a printing press, the combination of two alined press sections, angle-bars over which the webs printed by said sections may be turned and associated to run longitudinally of said sections, means located between said press sections for giving the associated webs a central longitudinal fold,
- means located between said two press sections for driving either or both of said sections, and means located at one end of said alined sections for alternatively driving either or both of said sections.
58. In a printing press, the combination of two alined press sections, angle-bars over which the webs printed by said sections may be turned and associated, means located between said two press sections for driving either or both of said sections, means located at one end of said alined sections for alternatively driving either or both of said sections, and other means located at the opposite end of said alined sections for alternatively driving either or both of said two sections.
59. In a printing press, the combination of two press sections, alined driving shafts 75 extending adjacent to said press sections, connections between said shafts and said press sections respectively for driving said press sections, an intermediate shaft in alinement with said two shafts, a fourth shaft 80 in alinement with said three shafts at one end, a fifth shaft in alinement with said four shafts at the opposite end, means for driving said intermediate shaft, other means for driving said fourth shaft, other means 85 for driving said fifth shaft, and means for connecting each two adjacent shafts as desired.
60. In a printing press, the combination of two press sections, alined driving shafts 90 extending adjacent to said press sections, connections between said shafts and said press sections respectively for driving said press sections, a third shaft in alinement with said two shafts at one end, a fourth 95 shaft in alinement with said three shafts at the opposite end, means for driving said third shaft, means for driving said fourth shaft, and means for connecting said shafts in series as desired.
61. In a printing machine, a plurality of press sections, a plurality of folders, a plurality of motors, and means for connecting the sections and folders with the motors to operate the machine with the sections in various groupings including a plurality of octuples, or a plurality of decuples, or a plurality of double sextuples.

Signed at Plainfield, in the county of Union and State of New Jersey, this 31st day of January, A. D. 1917.

DAVID JOHN SCOTT.
